UNITED STATES PATENT OFFICE.

HERMAN T. GREATHOUSE, OF LEXINGTON, KENTUCKY.

RELEASING DEVICE FOR LIVESTOCK.

Application filed April 30, 1925. Serial No. 27,009.

To all whom it may concern:

Be it known that I, HERMAN T. GREATHOUSE, a citizen of the United States, residing at Lexington, in the county of Fayette and State of Kentucky, have invented certain new and useful Improvements in Releasing Devices for Livestock, of which the following is a specification, reference being had to the accompanying drawings.

This invention relates to releasing devices for live stock and more particularly to a device of this character for automatically releasing live stock from an inclosure in event of fire.

An important object of the invention is to provide a device of this character having means set in operation by a fusible link or the like for simultaneously opening the doors of the inclosure and releasing the animals contained within the inclosure so as to permit them to leave by the opened doors.

A still further object of the invention is to provide a device of this character which may be manually operated whenever this is desired and which is very readily reset.

A further object of the invention is the provision of a device of this character which may be readily installed by persons having but slight mechanical skill, thus permitting direct purchase of such devices by dairy-men, farmers and the like and their installation without the necessity of hiring a skilled mechanic.

These and other objects I attain by the construction shown in the accompanying drawings, wherein for the purpose of illustration is shown a preferred embodiment of my invention and wherein:—

Figure 1 is a sectional view partially diagrammatic showing stock releasing mechanism constructed in accordance with my invention;

Figure 2 is a diagrammatic horizontal section through a building having an installation in accordance with my invention;

Figure 3 is a view showing the inner arrangement of a stall room door;

Figure 4 is an outer elevation of the stall room door;

Figure 5 is a detail of the latching mechanism of doors of this character;

Figure 6 is a detailed view of a halter rope holder; and

Figure 7 is a detailed front elevation of a sliding door operating weight holder.

Referring now more particularly to the drawings, the numeral 10 designates a building having a main sliding door 11 and an interiorly arranged stall room 12 having a swinging door 13. The stall rooms 12 may be provided in any desired number, one being herein illustrated. The stall door 13 should swing outwardly and is provided with a spring 14 moving the same to the open position when released. This stall door is fitted with an eye or eyes adjacent its free edge. In the present instance, two eyes are shown, designated at 15 and 16, and hereinafter referred to as the upper and lower eyes. Through the wall 17 of the stall adjacent the door frame and in vertical alignment with the eyes 15 and 16, openings 18 and 19 are formed. Through each of these openings, an arm 20 is directed, the upper arm having pivoted to its outer end a hasp 21 for engagement with the upper eye in a manner permitting the attachment thereto of a padlock 22 and to the lower arm is pivoted a hook 23 for engagement with the lower eye. If desired, two hooks or two hasps may be substituted instead of one hook and the hasp as shown.

Upon the interior of the stall wall above the door is pivoted a bell crank lever 24 having one arm thereof horizontally directed and the other arm vertically directed. To the horizontally directed arm is pivoted the upper end of a vertically extending link 25. Aligning with each opening 18 and 19, the inner face of the stall wall has secured thereto a U-shaped guide element 26 having vertically aligned apertures 27 formed in the arms 28 thereof. Above each of these brackets, the link 25 has a horizontal extension 29 terminating in a downwardly extending pin 30 directed through the openings 27. The inner end of each arm 20 has formed therein an opening 31 through which this pin may extend so that the pins serve to lock the arms in position through the wall and accordingly to prevent opening of the doors while the hooks or padlocks are engaged therewith.

It will be obvious that if the bell crank lever 24 is rocked on its pivot, the link 25 will be elevated and in such elevation will withdraw its pins 30 from the arms 20, freeing these arms and permitting the door to be opened under the influence of the spring 14. In order that these arms may not bind during the opening of the door,

the openings 18, 19, with which they are directed may be elongated through slots opening through the edge of the door frame, as more clearly shown in Figure 3. On the 5 interior of the stall, a bracket 32 affording spaced arms 33 is secured. These arms have aligned openings for the reception of a pin 34. This pin is connected to the horizontal arm of a bell crank lever 35 similar to the bell crank lever 24 and as will hereinafter be more fully explained, these bell crank levers will be simultaneously operated. This 10 pin will serve as a means for retaining between the arms the end of a halter rope or tether to which the animal confined within the stall is fastened and as the levers 24, 35, are simultaneously operated, the animal 15 will be released from its tether. At the same time, the door is released and permitted to open.

Secured to the sliding door 11, as at 36, is one end of a cable or similar flexible element 37. This cable is trained over a pulley 38 secured to the building wall. To the end 20 of this cable is secured a weight 39 having a reduced upper end 40, the upper extremity of which provides means for attaching the cable and the lower portion of which has formed therethrough an opening 41. A 25 bracket 42 is secured to the wall, this bracket embodying spaced arms 43 having aligned openings 44 receiving a pin 45. As will be hereinafter more fully set forth, the pin 45 is withdrawn from its engagement with 30 the weight and arms simultaneously with the withdrawal of the pins 30 and 34 so that both the stall door and main door of the inclosure are opened and the animal released at a single operation. The weight 39 will, 35 of course, be of sufficient weight to cause the opening of the door 11. Pivoted at any suitable point upon the structure 10 is a horizontally disposed shaft 46 having similarly directed angular arms 47 formed upon 40 the ends thereof.

Rigidly secured to this shaft intermediate the ends thereof is an operating arm 48 having a hand operating pull cord 49 secured to the free end thereof. Rotatably mounted 45 upon the rod 46, as at 50, is one end of a second operating arm 51, and is preferably of greater length than the arm 48 and provided intermediate its ends with a hook 52 which engages the arm 48 when the arm 51 50 is shifted to cause an operation thereof. Pivotally mounted upon the closure is a bent lever 53, one end of which is swingable into the path of the free end 55 of the second operating arm 51 to support the 55 same.

Means for holding the lever 53 in fixed position comprises a cable 56 directed through an eye 57 in the opposite end of the lever and passed about the inclosure at 60 various points where it will be most likely

to be subjected to fire. At intervals, this cable is provided with fusible links 58, the destruction of any one of which will release the cable permitting the lever 53 to swing about its pivot and releasing the second operating arm 51 permitting the same to move downwardly under the influence of a counter-weight 59 attached thereto. In its downward movement, this arm will bring its hook into engagement with the arm 48 70 thereof causing operation of the arm 48 and rotation of the rod 46.

It will be noted that the arm 48 may be operated independently of the arm 51, thus permitting of rotation of the rod 46. This 75 rod 46 has associated with the arms 47 thereof cables 60 and 61, the cable 60 being directed through eyes provided on the vertical arms of the bell crank levers 24, 35, and having at its free end a tension spring 62 attached 80 to the wall so that the cable 60 is drawn in a direction tending to move the arm 47 to its normal position. This cable, as the arm 47 to which it is attached is rotated upon 85 operation of either of the arms 48 or 51, moves in the direction of the arrow of Figure 1. Clamps 63 are secured to the cable of such size that they cannot pass through the eyes of the arms so that as the cable is drawn longitudinally under the influence of 90 the arm, these clamps come into engagement with the bell crank lever arms and cause the same to be operated to effect the release above described. The second arm 47 has secured thereto a cable 64 which is likewise 95 spring tensioned, as at 65, and has mounted thereon a ring 66 engaged by a clamp 67 similar to the clamp 63. This ring has secured thereto a cable or link 68, the opposite 100 end of which is connected with the pin 45 to withdraw the same when the rod 46 is actuated.

Attention is directed to the fact that additional arms 47 for the rod 46 might be applied and that, if desired, a further pull 105 cable 69 may be secured to the operating arm 48. Attention is further directed to the fact that the springs tend to return the shaft or rod 46 to its normal position and that accordingly when the mechanism is actuated through the operating arm 48, it will 110 return to its normal position after the arm is released, thus permitting the doors to be again locked and the stock to be secured within their stalls. Obviously, the halter 115 rope holders, such as indicated at 32, may be applied wherever this is found desirable and a number of cables 60, 61 and 69 extended to accommodate all of the doors and fastenings of the stable.

It will be noted that when the mechanism is actuated under the influence of the arm 51, this mechanism cannot be reset until the burned-out fusible link 58 has been restored, thus assuring that the mechanism is re- 120 125 130

turned to workable order. Since the structure hereinbefore set forth is obviously capable of a certain range of change and modification without materially departing 5 from the spirit of my invention, I do not limit myself to such specific structure except as hereinafter claimed.

I claim:

1. In a releasing device for live stock, an 10 inclosure including a plurality of restraining devices for preventing exit of the animals, separate means for retaining each restraining device in its restraining position, a connection between all of said means for 15 simultaneously releasing the same, a weight operated lever associated with said connecting means for operatively moving the same, fusible link restraining means for the weight operated lever and a hand operated lever for operating said connecting means independently of movement of the weight 20 operated lever.

2. In a releasing device for live stock and the like, a wall supported bracket including 25 spaced arms, a lever pivoted adjacent the bracket, a pin supported from the lever and directed through openings formed in the arms, a restraining device, said pin forming a means for retaining the restraining device in 30 restraining position, means for shifting the lever to withdraw the pin and release the restraining device for movement, including a pivoted shaft, an arm secured to said shaft, a second arm loosely mounted on the shaft, a 35 weight for operating said second arm, a hook carried by the second arm for engagement with the first named arm during its operation under the influence of weight to thereby operate the second arm and the 40 shaft, means including a fusible link restraining the second arm against operation and an operative connection between the lever and the shaft.

3. In a releasing device for live stock, a 45 plurality of restraining devices for the live stock, separate means for retaining each restraining device in its restraining position comprising a bracket including spaced arms having aligned openings and a pin directed 50 through the openings of the arms of each bracket and engaging the restraining device to prevent movement thereof to the releasing position, a weight operated lever, fusible link restraining means for the 55 weight operated lever, a hand operated lever and connections between all of said pins and each of said levers whereby the operation of either of the levers causes withdrawal of said pins and the hand operated lever may 60 be operated to withdraw said pins independently of movement of the weight operated lever, the connection between the hand operated lever and the pins including a spring restoring the hand operated lever to normal

position when released after an operation 65 to thereby permit reinstallation of the pins.

4. In a releasing device for live stock, an 70 inclosure including a plurality of restraining devices for preventing exit of the animals, separate means for retaining each restraining device in its restraining position, a connection between all of said means for 75 simultaneously releasing the same, a weight operated lever associated with said connecting means for operatively moving the same, fusible link restraining means for the weight operated lever and a hand operated lever for operating said connecting means independently of movement of the weight operated lever, the connection between said means 80 and the hand operated lever including a spring restoring the hand operated lever to normal position after an operation thereof and the connection to a position permitting 85 return of said retaining means to the retaining position.

5. In releasing means for live stock and in combination with a wall having an exit, a closure for the exit opening in one direction, a spring for moving the closure to the 90 open position, a pin loosely directed through the wall from that side thereof at which the closure opens, a pivoted hasp carried by the pin at the outer end thereof for engagement with the door for maintaining the same in closed position, a pair of arms carried by the wall at the opposite side thereof and between which the inner end of the pin projects, a securing element directed through said arms and pin at the inner face of the wall to prevent withdrawal of the pin and means for withdrawing said securing element.

6. In releasing means for live stock and in combination with a wall having an exit, a closure for the exit opening in one direction, a spring for moving the closure to the open position, a pin loosely directed through the wall from that side thereof at which the closure opens, a pivoted hasp carried by the pin at the outer end thereof for engagement with the door for maintaining the same in closed position, a pair of arms carried by the wall at the opposite side thereof and between which the inner end of the pin projects, a securing element directed through said arms and pin at the inner face of the wall to prevent withdrawal of the pin and means for withdrawing said securing element including a hand operated lever connected with the pin to withdraw the same, a weight operated lever associated with the hand operated lever and engaging the hand operated lever when operating under the influence of its weight to operate the hand operated lever and a fusible link restraining device for the weight operated lever.

7. In releasing means for live stock and

- in combination with a wall having an exit, a closure for the exit opening in one direction, a spring for moving the closure to the open position, a pin loosely directed through the wall from that side thereof at which the closure opens, a pivoted hasp carried by the pin at the outer end thereof for engagement with the door for maintaining the same in closed position, a pair of arms carried by the wall at the opposite side thereof and between which the inner end of the pin projects, a securing element directed through said arms and pin at the inner face of the wall to prevent withdrawal of the pin, means for withdrawing said securing element including a hand operated lever connected with the pin to withdraw the same, a weight operated lever associated with the hand operated lever and engaging the hand operated lever when operating under the influence of its weight to operate the hand operated lever and a fusible link restraining device for the weight operated lever, and means restoring the hand operated lever and its connection with the securing element to normal position when the hand operated lever is released to thereby permit reinstallation of the securing element.
8. In releasing means for live stock and in combination with a wall having an exit, a closure for the exit opening in one direction, a spring for moving the closure to the open position, a pin loosely directed through the wall from that side thereof at which the closure opens, a pivoted hasp carried by the pin at the outer end thereof for engagement with the door for maintaining the same in closed position, a pair of arms carried by the wall at the opposite side thereof and between which the inner end of the pin projects, a securing element directed through
- 5 10 15 20 25 30 35 40
- said arms and pin at the inner face of the wall to prevent withdrawal of the pin, means for withdrawing said securing element including a hand operated lever connected with the pin to withdraw the same, a weight operated lever associated with the hand operated lever and engaging the hand operated lever when operating under the influence of its weight to operate the hand operated lever and a fusible link restraining device for the weight operated lever, and means restoring the hand operated lever and its connection with the securing element to normal position when the hand operated lever is released to thereby permit reinstallation of the securing element, the weight operated lever being sufficient to permit the action of the last named means and prevent return of the connection and hand operated lever to their normal position until the fusible link restraining device has been restored.
9. In a releasing device for live stock and the like, a restraining device, a retaining element for the restraining device including a movable pin means, for withdrawing said pin to release the restraining device including a hand operated lever, an operative connection between the hand operated lever and the pin for drawing the pin upon movement of the lever, a weight operated lever having a portion engaging the hand operated lever to operate the same when the weight operated lever operates under the influence of its weight and means including a fusible link for restraining the weight operated lever from movement.
- 65 70 75
- In testimony whereof I hereunto affix my signature.

HERMAN T. GREATHOUSE.
